UNITED STATES PATENT OFFICE.

JAMES JONES FAULKNER AND ELZA TAYLOR FAULKNER, OF McMINN-
VILLE, TENNESSEE.

MACHINE FOR TREATING MIDDLEDINGS.

SPECIFICATION forming part of Letters Patent No. 293,236, dated February 12, 1884.

Application filed May 18, 1883. (No model.)

To all whom it may concern:

Be it known that we, JAMES JONES FAULKNER and ELZA TAYLOR FAULKNER, both of 5
McMinnville, county of Warren, and State of Tennessee, have invented a new and useful
Improvement in Machines for Treating Middleddings, of which the following is a clear, full,
and exact description, reference being had to the accompanying drawings, making a part of
10 this specification, in which—

Figure 1 is a perspective view of a flour-bolt with our improvements attached, and with outer casing removed. Fig. 2 is an end elevation of our machine. Fig. 3 is a transverse vertical section through $\alpha\alpha$ of Fig. 1. Fig. 4 is a longitudinal vertical section.

Our invention relates to machines for bolting flour and purifying middlings; and it consists of the several combinations of devices, 20
hereinafter explained and claimed.

To enable others skilled in the art to make and use our invention, we will proceed to describe the exact manner in which we have carried it out.

25 In the drawings, A represents the framework of a flour-bolting chest with the outer casing removed, so as to show the interior structure. Through the center of the bolting-chest runs longitudinally the supporting-bar B, on which rests, and to which is secured, the sieve or bolting-cloth C. Two parallel plates or bars, b b, hold the outer edges of the sieve, and the cross-bars b' b', passing at right angles over the center bar, B, and attached to the 30 parallel bars b b, support the body of the sieve. At one edge of the bolting-cloth or sieve is fastened a strip of rubber cloth or other elastic material, D, by sewing or otherwise, for the purpose of keeping the cloth C always 35 tightly stretched, equally in dry and wet weather. The sieve is transversely inclined at any desired angle toward the elevator-box E, but is on a level longitudinally. The central or supporting bar, B, extends beyond each 40 end of the frame, for a purpose hereinafter explained, and has its bearings in cross-beams F F'. Across one end of the machine is the shaft G, having its bearings in the arms g g, extending out from the frame A. To one end 45

of this shaft is attached the band-wheel G', 50 and near its center is secured the eccentric g', bearing against an adjustable knocker, H, which is attached to the rocker-shaft H', having its bearings in the eyes h h, attached to the frame below the shaft G. The knocker H has 55 a set-screw, h', by which it may be adjusted to bear more or less against the eccentric g', and give the sieve a longitudinal vibrating motion by knocking against the exposed end of the supporting-bar B. On the opposite end of 60 our machine we attach a double-wire spiral spring, I, which is wound both right and left around and toward the center of the shaft i, with a central loop, i', in the center of the wire, to form a lever to bear against the exposed 65 end of the middle or supporting bar, B, of the sieve, to counteract or reciprocate the vibrating motion of the eccentric and knocker at the opposite end of the sieve. The shaft i, on 70 which the wire spring is formed, has bearings with set-screw d, (see Fig. 1,) the purpose of which is to tighten the shaft firmly in its bearings. Now, by turning this shaft, after releasing it from the set-screw d, the spring can 75 be strengthened or weakened, according to the way the shaft may be turned, and the shaft can then be again firmly fixed at any degree of inclination that may be desired by again tightening the set-screw d, the wire spring being rigidly attached to the shaft. Longitudinally 80 through the upper part of the machine passes a shaft, J, on the outer ends of which are the band-wheels j j, by which motion is given to the shaft and through the shaft to the auger-twist conveyers in the bottom of the machine. 85 On the shaft J we secure two or more sprocket-wheels, K, carrying suitable belts, k, to which are attached the long elevator-buckets L. Within the elevator-box E is a shaft, M, carrying a like number of sprocket-wheels, around 90 which passes the belt k, and by means of which the elevator-buckets are caused to pass through the elevator-box and return the middlings or flour to the top of sieve, to be worked over again and again until they are thoroughly 95 worked, the bran and fluff all the while working toward the tail end of the purifier and dropping over the end of the sieve into the

discharge-spout N for impurities. The sieve C having a lateral inclination instead of a longitudinal one, the middlings or flour placed thereon to be cleaned of fluff, bran, or foreign substances glides freely on the incline by its own gravitation. The middlings or flour, being of greater specific gravity than the bran or fluff, occupies a position next the sieve while passing over the cloth, at the same time forcing the fluff and bran to move on top, as if floating on water. The middlings and flour, in the meantime passing through the sieve, are thus separated from all impurities. Such part of the middlings and flour as may fail to pass through the sieve will fall from the lower edge into the long elevator-box, whence it will be again returned to the top edge of the sieve, to be worked over. Before reaching the top edge of the sieve, it falls from the elevator-buckets onto the interposed wicket-board P, which distributes the middlings or flour evenly upon the sieve. This wicket-board is pivoted at each end of the machine, so that it may receive any desired lateral incline necessary to cause an even flow of the material on the face of the sieve at its upper side.

We have ascertained by actual experiments that by the working of the bran in with the middlings we secure an excellent collection of the

fluff. The bran acts upon and attracts the fluff, which we are enabled to collect perfectly without the use of a fan, which is employed in all purifiers.

Having thus described our invention, what we claim as new, and desire to secure by Letters Patent, is—

1. In a middlings-purifier, the sieve C, having a lateral incline, and provided with the central supporting-bar, B, parallel bars b b, and cross-bars b' b', in combination with the knocker H and eccentric g' at one end and the spring I at the other, substantially as and for the purpose herein described.

2. The sieve C, having a lateral inclination, in combination with the supporting-bar B, parallel bars b b, cross-bars b' b', knocker H, and spring I, all constructed to operate substantially as and for the purpose set forth.

3. The knocker H, in combination with the shaker, the rocker-shaft H', set-screw h', and eccentric g', all constructed to operate substantially as and for the purpose set forth.

JAMES JONES FAULKNER.
ELZA TAYLOR FAULKNER.
